AUTOMATIC CATHODE VOLTAGE
ADJUSTING DEVICE

Lewis J. McKesson, Port Jefferson, N. Y., assignor
to Radio Corporation of America, a corporation
of Delaware

Application December 15, 1938, Serial No. 245,838

3 Claims. (Cl. 250—27)

This invention relates to a power supply for a thermionic discharge tube and, more particularly, to a means for automatically adjusting the voltage applied to the thermionic cathode in accordance with the space discharge current through the tube.

In present radio transmitters and in other circuits using thermionic discharge tubes the filament voltage of the thermionic discharge tube is adjusted to a fixed value depending upon the maximum emission desired from the cathode. Under such conditions the filament voltage is established at the value corresponding to maximum emission and this voltage remains constant even though the emission is reduced or made zero by cutting off plate current. In actual practice this condition may be especially bad due to poor power supply regulation. Under such conditions the filament voltage will actually decrease with an increase in plate current.

An object of my invention is to overcome the heretofore mentioned difficulties.

Another object of my invention is to provide a means for automatically adjusting the filament voltage of a thermionic discharge tube in accordance with the space discharge current through the tube.

Still another object of my invention is to increase the useful life of vacuum tubes in radio transmitters and other services by automatically adjusting the emission capability of the cathode in accordance with the space current through the tube.

Briefly, my device consists of a means for varying the voltage supply to the filament of a thermionic discharge tube in accordance with the plate current of the tube. This may be done either by means of a variable impedance which is automatically varied in accordance with the plate current, or it may include a number of fixed impedances of different values which may be selectively switched into the filament circuit in accordance with the plate current of the tube.

A more complete understanding of my invention will be had by reference to the following detailed description which is accompanied by drawings in which Figure 1 illustrates an embodiment of my invention, while Figure 2 illustrates a modification of the form of my invention shown in Figure 1, while Figures 3 and 4 show further modifications of my invention.

Referring, now, to Figure 1, reference numeral 1 represents a thermionic discharge tube having a plate 2, a grid 3 and a filament 4. Obviously, the filament 4 may be replaced by an indirectly

heated cathode having a heating filament, if desired. The filament 4 is energized through a filament transformer 5 which is connected to the A. C. filament supply line 7, 7 through a variable resistance 6. The variable resistance is used to fix the maximum operating value of the voltage supply to the filament 4. Also, in series with the filament transformer and the filament supply in a saturation choke coil 8. This choke coil comprises an iron core having wound thereon 10 windings 9 and 10. These windings are on the outer legs of the coil and arranged in opposing relationship. On the center leg of the iron core is wound a direct current winding 11. The relationship of the windings 9, 10 and 11 is such that zero voltage is induced in the center coil which is designed to carry the direct current. The coil 11 is connected between the center tap of transformer 5 and the negative side of the direct current plate supply 12. The positive side 20 of the plate supply is connected through choke 13 to plate 2. Variations in the plate current to the vacuum tube 1 will induce equal and opposite voltages in the outside coils 9 and 10 of the saturation choke coil 8. The direct current 25 in the center coil 11 varies the magnetic flux through the closed magnetic circuit which, due to the variation in the slope of the saturation curve of the iron core will in turn vary the inductance of the alternating current coils 9 and 30 10 and thereby vary the effective impedance and the current flowing therethrough. This action is such that an increase in the plate current to the vacuum tube reduces the impedance of the unit and produces a higher filament voltage 35 across the terminals of filament 4.

By means of a variation in the dimensions of the saturation choke coil, the variation in voltage may be adjusted to follow any predetermined law. Also, by insertion of variable 40 resistors, air gaps or magnetic shunts, the designs may be adjusted to give various degrees of controlling action.

Figure 2 shows a modification of the embodiment shown in Figure 1 which is particularly 45 adaptable for use in cases where the anode current of the vacuum tube is of itself insufficient to be used indirectly as a controlling force. An example of a tube of this type is an X-ray tube. In this modification a fixed resistor 14 is placed 50 in series with the direct current plate supply. The voltage drop through this resistor 14 is then applied to a direct current amplifier 15 and the resultant amplified direct current is then applied across coil 11. Except for this variation, the 55

modification shown in Figure 2 is the same as in Figure 1.

In certain cases in order to save space and reduce losses it may be desirable to combine the 5 filament transformer 5 and the saturation choke coil into a single structure as shown in Figure 3.

The embodiment of my invention illustrated in Figure 3 includes a filament transformer 38 having a conventional primary 39 and a conventional 10 secondary 35. On the same core with these two windings are two additional windings 31 and 31'. Winding 31' is connected through a resistance 36 to an auxiliary D. C. supply 32. The variable resistance 36 is suitably adjusted so that the core 15 of transformer 38 is saturated to the proper extent to reduce the filament voltage to the required no load condition. Winding 31 is connected in series with the direct current plate supply to the thermionic discharge tube 1 and 20 serves a similar purpose to that served by coil 11 in Figure 1. Coil 31 is so polarized as to buck the winding 31'. Therefore, an increase of current through coil 31 effectively decreases the saturation of the core of the transformer 38 and 25 thereby causes an increase in the current applied to filament 4. If desired, a condenser C may be placed across coil 31 or a filter interposed in this circuit in order to prevent any possibility of hum modulation of the plate supply by alternating currents induced in coil 31.

Another embodiment of my invention, which does not involve the use of any direct current saturating coils, is illustrated in Figure 4. In this modification a transformer 40 has one winding 40' connected in series between the filament 35 transformer 5 and the alternating current filament supply 1, 1. The other winding 41 of transformer 40 is connected in series between the plate transformer 43 and the alternating 40 current supply 42 of the plate. The secondary of plate transformer 43 is connected to rectifier 44 and the output of rectifier 44 is applied to the plate circuit of thermionic discharge tube 1 in the conventional manner. Across winding 41 of transformer 40 is connected a variable resistance 46. The two windings of transformer 40 are so poled that as the current drawn from the alternating current plate supply 42 is increased 45 an additional voltage is applied in series with the filament supply 1, 1 by means of the winding 40', thus adjusting the filament voltage to the needs of the tube under the increased load. By means of variable resistance 46 connected across the winding 41 it is possible to adjust the compensation to the required amount.

As a further modification within the scope of my invention, saturation choke coil 8 may be replaced by a relay so connected that a series resistance in the filament supply circuit is short 50 circuited or the ratio of an auto transformer in the filament supply circuit adjusted by an increase of plate current. If desired, where poly-phase filament supply is used the saturation reactor for each leg of the filament supply may be 55 combined into a single structure using only a single direct current magnetizing coil.

While I have particularly described my invention with respect to vacuum tube devices such as used in a radio transmitter, it is obvious that my device may be applied to various other types of vacuum tube devices such as rectifier tubes of 5 either the vacuum or gaseous types, cathode ray tubes, X-ray tubes, bombardment tubes, or any other such device in which space current is drawn intermittently and in which it is desired to increase the life of the cathode or filament. 10

While I have described and shown several modifications of my invention it should be clearly understood that other modifications within the scope of my invention may be made.

I claim:

1. In combination, a thermionic discharge tube having at least an anode and a cathode, a source of alternating current for energizing said cathode, a first source of direct current for said anode, a transformer interposed between said 20 source of alternating current and said cathode, said transformer having a pair of auxiliary windings, a second source of direct current for energizing one of said windings, the other of said windings being connected between said first 25 source of direct current and said cathode, said auxiliary windings being arranged in bucking relationship whereby an increase in the anode current of said tube causes an increase in the voltage applied to said cathode. 30

2. In combination, a thermionic discharge tube having at least an anode and a cathode, a source of alternating current for energizing said cathode, a first source of direct current for said anode, a transformer interposed between said 35 source of alternating current and said cathode, said transformer having a pair of auxiliary windings, a second source of direct current, means for energizing one of said windings from said second source of direct current, the other of said auxiliary windings being connected between said first source of direct current and said cathode, said auxiliary windings being arranged in a bucking relationship whereby an increase in the anode 40 current of said tube causes an increase in the voltage applied to said cathode. 45

3. In combination, a thermionic discharge tube having at least an anode and a cathode, a source of alternating current for energizing said cathode, a first source of direct current for said 50 anode, a transformer interposed between said source of alternating current and said cathode, said transformer having a pair of auxiliary windings, a second source of direct current, means for energizing one of said windings with direct current from said second source, the other of said auxiliary windings being connected between said first source of direct current and said cathode, said auxiliary windings being arranged in a bucking 55 relationship whereby an increase in the anode current of said tube causes an increase in the voltage applied to said cathode and means connected to said other auxiliary winding for preventing alternating currents induced therein from modulating said anode current. 60
